LIFE PRESERVER

Jules Catarau, Seattle, Wash.

Application December 12, 1931. Serial No. 580,648

9 Claims. (Cl. 9—17)

The main object of this invention is to provide a life preserver which can be instantaneously adjusted on the body of a person and at the same time securely fastened by a single quick action delivered by one hand.

A further object of the invention is to provide the life preserver with such fastening means as will permit said life preserver to be operated with either side next to the body and regardless of the size and shape of the said body.

Furthermore, one of the several objects of the invention is to design the body member of the life preserver and to dispose the fastening appurtenances so that said life preserver may be worn in its requisite position and concealed indefinitely underneath any wearing apparel without creating an incongruity in the correct appearance of the wearer's toilet.

A life preserver constructed in accordance with this invention is substantially illustrated in the drawings comprising three sheets accompanying this application.

The Figure 1 of the drawings thereof is a plane elevation of said life preserver unfolded.

Figure 2 illustrates said life preserver adjusted in requisite position on the body of a person.

Figure 3 is an enlarged plane view of the fastening means supplied by preference in this invention.

Figure 4 exposes a cross-section of broken line 11—11 of Fig. 3.

Figure 5 is a plane elevation of said life preserver unfolded and showing a modification in the arrangement of its fastening means.

Figure 6 illustrates the life preserver adjusted on the body of a person after the alteration has been made in its fastening means.

Figure 7 illustrates an additional fastening combination supplied for said life preserver in view of the alteration in its fastening means as shown in Figures 5 and 6.

Figure 8 exposes a cross-section of broken line 12—12 of Figure 7.

Figure 9 is a plane elevation of said life preserver unfolded and showing its original combination with two straps in co-action with the additional fastening means illustrated in the Figures 7 and 8, said additional fastening means simplified in view of cheapness of its manufacture.

Figure 10 illustrates said simplified additional fastening combination on an enlarged scale.

Similar numerals refer to similar parts throughout the drawings.

The body member of the life preserver consists

of an envelope endued with the capital property of buoyancy and adapted to envelop the body of a person on and above the waist line and to terminate over the chest with two erect extensions spaced to avoid the interference of said envelope with the correct appearance of the wearer's toilet. These extensions are intended to augment the buoyancy in front and thereby to bring and hold the wearer—when in water—in a safe position, erect and slightly inclined backward.

In order to permit the wearing of life preserver concealed underneath any wearing apparel without creating an incongruity in the toilet of the wearer, the buoyancy is obtainable through inflation and the envelope is perfectly collapsible when deflated. A longitudinal partition, or partitions, divide the inflatable envelope into two independently inflatable chambers, subjacent 14 and superjacent 15. The specified division is intended to lessen the danger occurring from the vulnerability of any such envelope and from possible imperfection in the means for inflation especially when self-inflating device is used. Said chambers are each of such expansion and disposition around the body that the proper inflation of either chamber will insure sufficient buoyancy and equilibrium necessary for the successful performance of the life preserver.

For adjustment and fastening of the life preserver on the body two identical straps 16 16 are provided and integrated each by one end to the two erect extensions respectively and purposed to be worn about the neck in a yoke-like manner; ascending, each over a shoulder, passing behind the neck through the frame 17, and returning, each doubled upon itself, toward their points of departure respectively to be fastened to the envelope in front. The connection of the frame 17 with the envelope is optional and as illustrated in the Figure 9 of the drawings said frame 17 may consist of two frames 17a and 17c, one for every strap 16, said frames 17a and 17c being securely connected together by the intermediate portion 17b. The connection of the members 17a, 17b, and 17c with the envelope remains also optional.

Frames 18 18 are secured to the envelope and adapted each to retain slidably one of the loose ends of the straps 16 16. One way engaging pawls 19 19 are arranged in the frames 18 18 so as to permit said straps to slide freely through the said frames forward only. A tongue 20 projects from each pawl 19 and facilitates the lifting of said pawls against their springiness so as to release their permanent grip on the straps 16 16.

and thereby enable the removal of the life preserver.

To facilitate a better gripping of said pawls 19 19 on the straps 16 16 a plurality of bulges, or the like, 21 21 21 is formed in series on a convenient portion of said straps.

The tips of the loose ends of the straps 16 16 are provided each with a stopper 22 and retained each by a ring, or the like, 23, the rings thereof being secured to the envelope on a convenient location in order to prevent the elusion of said ends out of hand's reach, and also to facilitate their handling when the life preserver happens to be worn with the straps next to the body.

15 This combination with the stoppers 22 22 and the rings 23 23 is claimed in the application for a life preserver, said application filed April 3, 1930, Serial No. 441,245, and allowed June 15, 1931.

20 Such an arrangement in the fastening means insures for the life preserver the possibility of being instantaneously adjusted and at the same time fastened in its requisite position on the body, but the operation requires simultaneous 25 co-action of both hands or repeated action of one hand. To accomplish said operation by a single quick-action delivered by one hand the following modification in the arrangement of the fastening means is envisaged. One of the 30 straps 16 16 and its respective frame 18 are discarded as shown in the Figures 5 and 6 of the drawings. The remaining strap 16 is elongated to extend behind the neck and over the other shoulder and to be retained slidably by the frame 35 24, said frame 24 secured to the envelope at the place where the discarded frame 18 stood. A quick downward pull delivered by one hand on the loose end of the single strap 16 will give the result obtainable in the original combination through the use of both hands or the 40 repeated action of one hand.

In the modified arrangement of the fastening means the frame 17 may be discarded or used connected with the medial portion of the envelope as shown in the Figure 5 of the drawings.

45 In the original combination with two straps the loose ends of the said straps for better security may be fastened together in front. In view of the fact that this advantage is lacking in the combination with one strap, additional fastening means are supplied. Said means comprises a tape, or like appendage, 25 secured to the envelope on a convenient location, a plurality of bulges, or the like, 26 26 26 formed in series 50 on the said tape 25 preferably by knotting the same in a convenient manner as shown in Fig. 7, and a "gapped" frame 27 secured to the envelope on a convenient location and adapted to receive (catch) said tape 25 in a latch-like manner and retain it by one of the bulges 26. Said frame 27 rests rigidly on the surface of the envelope to which it is secured preferably by embedding the base-portion 28 into the envelope. The medial portion 29 of said frame is pressed close to the surface of the envelope in order to prevent the escape of the tape 25 from within the gap 30. The prominence 31 ends with a gradual rising from the level surface of the envelope in order to lead the way into the gap 30 and ease the latching.

55 A bite 32 is cut in the side edge of said frame for better grasping of the bulge 26 by which tape 25 is retained.

60 A barb-like projection 33 (Figs. 7, 8, and 10) intervenes in the middle of the gap 30 so as to

prevent indubitably the escape of the tape 25 out of the said gap 30. Said projection 33 may be an appurtenance of the frame 27 or of the envelope.

65 Frame 27 furnished in plurality on the parts to be connected together will enable tape 25 to lace rapidly said parts together, tape 25 being elongated for the occasion.

70 As the life preserver is wearable either side out, frame 27 is furnished on both faces of the envelope.

75 This additional fastening combination with the tape 25, bulges 26, and frame 27, is capable to perform independently in any life preserver of the category. If appropriated for co-action in the life preserver with combination of two straps, as shown in Figures 1 and 2 of the drawings, the rings 23 23 may be discarded and the stoppers 22 22 shifted close to the frames 18 18 as shown in the Figure 10.

80 The bulges 21 formed in series on the straps 16 and the bulges 26 formed in series on the tape 25 are supplied in convenient plurality to cope with the variation in the size and shape of the wearers' bodies.

85 What I claim as my invention is:

1. A life preserver, consisting in an envelope endowed with the property of buoyancy and adapted to envelop the body of a person on and above the waist line, a combination of said envelope and two identical straps integrated each by one end to the said envelope in front and purposed to be worn about the neck in a yoke-like manner; ascending, each over a shoulder, to pass freely behind the neck through a coupling frame, and returning, each doubled upon itself, toward their points of departure respectively to be fastened to said envelope in front; said coupling frame retaining slidably both said straps.

90 2. A life preserver, consisting in an envelope endowed with the property of buoyancy and adapted to envelop the body of a person on and above the waist line, a combination of said envelope and two identical straps integrated each by one end to the said envelope in front and purposed to be worn about the neck in a yoke-like manner; ascending, each over a shoulder, to pass freely behind the neck through a coupling frame, and returning, each doubled upon itself, toward their points of departure respectively to be fastened to said envelope in front; said coupling frame retaining slidably both said straps and being connected to the medial portion of said envelope.

95 3. A life preserver, consisting in an envelope endowed with the property of buoyancy and adapted to envelop the body of a person on and above the waist line, a combination of said envelope and two identical straps secured each by one end to the said envelope in front and purposed to be worn about the neck in a yoke-like manner; ascending, each over a shoulder, to pass freely behind the neck each through a frame, and returning, each doubled upon itself, toward their points of departure respectively to be fastened to said envelope in front; the frames thereof each retaining slidably one of said straps and being securely connected together.

100 4. A life preserver, consisting in an envelope endowed with the property of buoyancy and adapted to envelop the body of a person on and above the waist line, a combination of said envelope and two identical straps secured each by one end to said envelope in front and purposed to be worn about the neck in a yoke-like manner;

ascending, each over a shoulder, to pass freely behind the neck each through a frame, and returning, each doubled upon itself, toward their points of departure respectively to be fastened 5 to said envelope in front; the frames thereof each retaining slidably one of said straps and being connected together and with the medial portion of said envelope.

5. A life preserver, consisting in an envelope 10 endowed with the property of buoyancy and adapted to envelop the body of a person on and above the waist line, a combination of said envelope and a strap secured by one end to said envelope in front and purposed to be worn about the neck 15 in a yoke-like manner; ascending over a shoulder, passing behind the neck, extending over the other shoulder through a frame, and returning, doubled upon itself, toward its point of departure to be fastened to said envelope in front; the frame 20 thereof retaining slidably the medial portion of said strap and being secured to said envelope in front.

6. A life preserver, consisting in an envelope 25 endowed with the property of buoyancy and adapted to envelop the body of a person on and above the waist line, a combination of said envelope and a strap secured by one end to said envelope in front and purposed to be worn about the neck in a yoke-like manner; ascending over a shoulder 30 to pass freely behind the neck through a frame, extending over the other shoulder to pass freely through another frame, and returning, doubled upon itself, through the frame behind the neck toward its point of departure to be fastened to 35 said envelope in front; the frame behind the neck retaining slidably the rear and forward portions of said strap and being connected with medial portion of said envelope; the other frame retaining slidably the medial portion of said strap and 40 being securely connected to the said envelope in front.

7. A life preserver, consisting in an envelope 45 endowed with the property of buoyancy and adapted to encircle the body of a person on and above the waist line, a combination of said envelope and a strap secured by one end to the said en-

velope in front, said strap ascending over a shoulder, passing freely through a frame connected with the rear part of said envelope, said strap then returning doubled upon itself toward its point of departure to pass its active end through another frame; said active end having a plurality of bulges set in series; said another frame being secured to the front of the envelope and having a pawl descending obliquely so as to oppose the backward sliding of said strap; the pawl thereof having an outwardly projecting tongue and an acute edge reaching the base of said bulges close at the surface of the strap.

8. A life preserver, consisting in an envelope 85 endowed with the property of buoyancy and adapted to encircle the body of a person on and above the waist line and connected over the shoulders, a combination of said envelope and a tape, or like appendage, and a hook-like gapped frame; said tape being secured by one end to a convenient part of said envelope and having a plurality of bulges set in series, said hook-like frame being secured to another portion of said envelope and having its middle portion close to the surface of the envelope and its point rising gradually from the level surface of the envelope so as to receive (catch) said tape in a latch-like manner.

9. A life preserver, consisting in an envelope 100 endowed with the property of buoyancy and adapted to encircle the body of a person on and above the waist line and connected over the shoulders, a combination of said envelope and a tape, or like appendage, and a hook-like gapped frame; said tape being secured by one end to a convenient part of said envelope and having a plurality of bulges set in series, said hook-like frame being secured to another portion of the envelope 105 and having its point 31 rising from the level surface of the envelope so as to receive (catch) said tape in a latch-like manner, and a barb-like projection intervening in the gap of the said hook-like frame, to prevent the escape of said appendage.
